UNITED STATES PATENT OFFICE.

ELZY M. WOLFF, OF MANSFIELD, OHIO.

DESIGN FOR A MONUMENT.

SPECIFICATION forming part of Design No. 34,051, dated February 5, 1901.

Application filed August 1, 1900. Serial No. 25,479. Term of patent 3½ years.

To all whom it may concern:

Be it known that I, ELZY M. WOLFF, a citizen of the United States, residing at Mansfield, in the county of Richland and State of Ohio, have invented and produced a certain new and useful Design for Monuments, of which the following is a specification.

In the accompanying drawings, Figure 1 is a side elevation of my new and originally designed monument, showing its essential features. Fig. 2 is an end view of same, the bases A and C removed to show more fully the complete design of the monument.

The monument consists of the base A, which is rectangular, the corners B rounded. The second base C is also rectangular to conform to the lower base A and is provided with the molding D, carved, the upper edge provided with a denticulated molding E. The third section F is provided at each corner with a carved base G.

The die H consists of a rectangular block plain upon the face of the walls. Each corner is provided with a pilaster I, carved as shown. The said pilasters are the same in design upon the ends of the monument, as shown in Fig. 2. Each pilaster is provided with a capital J, which forms part of the center die

H. Extending across the face of the capitals and the end of the monument is the crown-molding L, carved as shown in the drawings. The said crown-molding is surmounted by a foliated molding M, from which emerges the volutes N, with curved antefixa O projecting above the foliated molding, and at each corner of the die H, resting upon the capitals at the front and back of the die, are the curved moldings P. The said moldings are carved with fleur-de-lis. The lower edge of said molding is provided with the beaded fillet Q. The upper surface of the cap R is convex longitudinally and on the cross-section, the front and back of the cap rounded upon the edge and cut under to a line with the back of the curved molding P.

Having fully described my new monumental design, what I claim is—

The design for a monument substantially as illustrated and described.

In testimony whereof I affix my signature in presence of two witnesses.

ELZY M. WOLFF.
